PROJECTION TYPE WEIGHING SCALE

Richard F. Straw, Rutland, Vt., assignor to The Howe Scale Company, Rutland, Vt., a corporation of Delaware

Application December 19, 1955, Serial No. 39,386

Term of patent 14 years

(Cl. D52—10)

Fig. 1 is a side elevational view of a projection type weighing scale showing my new design.

Fig. 2 is a front elevational view.

Fig. 3 is a top plan view.

I claim:

The ornamental design for a projection type weighing scale, substantially as shown.
